(57) **CLAIM**

An ornamental design for a steamer body, as shown and described.

DESCRIPTION

FIG. 1 is a front top left perspective view of a steamer body showing our new design therefor, the bottom plate and handle being shown in phantom line and forming no part of the design;

FIG. 2 is a top plan view thereof;

FIG. 3 is a side elevational view thereof, the presser plate being shown in phantom line and forming no part of the design for this and for all of the other figures where the presser plate is shown as an environmental feature only, the opposite side being an identical mirror image thereof;

FIG. 4 is a front elevational view thereof;

FIG. 5 is a rear elevational view thereof;

FIG. 6 is a view similar to FIG. 1 of a second embodiment of the invention with the bottom plate shown in phantom line and forming no part of the design;

FIG. 7 is a top plan view thereof;

FIG. 8 is a side elevational view, the opposite side being an identical mirror image thereof;

FIG. 9 is a front elevational view thereof; and,

FIG. 10 is a rear elevational view thereof.
